[57] CLAIM

The ornamental design for a suspended ceiling, as shown and described.

DESCRIPTION

FIG. 1 is a fragmentary bottom perspective view of a suspended ceiling illustrating a new design of my invention;

FIG. 2 is a fragmentary bottom plan view thereof, the pattern of the suspended ceiling is repetitive as shown in FIG. 2 of the drawing disclosure;

FIG. 3 is an enlarged fragmentary top perspective view of the connector assembly shown in FIG. 1;

FIG. 4 is a fragmentary side elevational view as viewed from the left side of FIG. 2;

FIG. 5 is a fragmentary top plan view thereof, without any ceiling tile in position supported by rails; and,

FIG. 6 is a fragmentary top plan view, similar to FIG. 5, but illustrating the ceiling panels in position supported by the rails.

FIG. 1

FIG. 2

FIG. 3

FIG. 4

FIG. 5

FIG. 6
